UNITED STATES PATENT OFFICE

105,872

DESIGN FOR A TEXTILE FABRIC

Walter A. Hughes, New York, N. Y.

Application July 30, 1937, Serial No. 70,738

Term of patent 3½ years

To all whom it may concern:

Be it known that I, Walter A. Hughes, a citizen of the United States of America, residing in the city of New York, State of New York, have invented a new, original, and ornamental Design for a Textile Fabric, of which the following is a specification, reference being had to the accompanying drawing, forming part thereof, wherein, the figure is a plan view of a piece of textile fabric showing my new design.

I claim:

The ornamental design for a textile fabric substantially as shown.

WALTER A. HUGHES.
